CLAIM

The ornamental design for a cup sole for a shoe, as shown and described.

DESCRIPTION

FIG. 1 is a side elevational view of one side of a cup sole for a shoe showing one embodiment of my new design; FIG. 2 is a side elevational view of the other side of the cup sole for a shoe as shown in FIG. 1; FIG. 3 is a front elevational view of the cup sole for a shoe as shown in FIG. 1; FIG. 4 is a rear elevational view of the cup for a shoe as shown in FIG. 1; FIG. 5 is a bottom plan view of the cup sole for a shoe as shown in FIG. 1; FIG. 6 is a side elevational view of one side of a cup sole for a shoe showing another embodiment of my new design; FIG. 7 is a side elevational view of the other side of the cup sole for a shoe as shown in FIG. 6; FIG. 8 is a front elevational view of the cup sole for a shoe as shown in FIG. 6; FIG. 9 is a rear elevational view of the cup sole for a shoe as shown in FIG. 6; FIG. 10 is a bottom plan view of the cup sole for a shoe as shown in FIG. 6; FIG. 11 is a side elevational view of one side of a cup sole for a shoe showing another embodiment of my new design; FIG. 12 is a side elevational view of the other side of the cup sole for a shoe as shown in FIG. 11; FIG. 13 is a front elevational view of the cup sole for a shoe as shown in FIG. 11; FIG. 14 is a rear elevational view of the cup sole for a shoe as shown in FIG. 11; and FIG. 15 is a bottom plan view of the cup sole for a shoe as shown in FIG. 11. The broken line showing of a shoe in FIGS. 1, 2, 6, 7, 11 and 12 is for illustrative purposes only and forms no part of the claimed design.
